(57) **CLAIM**

We claim the ornamental design for a dispenser housing, as shown and described.

DESCRIPTION

FIG. 1 is a front perspective view of the dispenser housing in an open configuration, showing our new design, the dispenser housing including broken lines which are used in the present drawing and throughout the drawings to represent environment and which form no part of the claimed design;

FIG. 2 is a front perspective view thereof in a closed configuration;

FIG. 3 is a top plan view thereof;

FIG. 4 is a front elevation view thereof;

FIG. 5 is a side elevation view thereof taken from the right of FIG. 4;

FIG. 6 is a rear elevation view thereof;

FIG. 7 is a side elevation view thereof taken from the left of FIG. 4; and,

FIG. 8 is a bottom plan view thereof.

1 Claim, 5 Drawing Sheets

See application file for complete search history.
